CLAIM

The ornamental design for a rotatable jewelry cabinet, as shown and described.

DESCRIPTION

FIG. 1 is a front view of a rotatable jewelry cabinet showing my new design;

FIG. 2 is a rear view of the rotatable jewelry cabinet of FIG. 1;

FIG. 3 is a left side view of the rotatable jewelry cabinet of FIG. 1;

FIG. 4 is a right side view of the rotatable jewelry cabinet of FIG. 1;

FIG. 5 is a bottom view of the rotatable jewelry cabinet of FIG. 1;

FIG. 6 is a top view of the rotatable jewelry cabinet of FIG. 1;

FIG. 7 is a first perspective view of the rotatable jewelry cabinet of FIG. 1;

FIG. 8 is a second perspective view of the rotatable jewelry cabinet of FIG. 1, with upper part of the rotatable jewelry cabinet in a rotated configuration; and,

FIG. 9 is third perspective view of the rotatable jewelry cabinet of FIG. 1, with drawers of the rotatable jewelry cabinet in an open configuration.

The broken lines shown in the drawings are for the purpose of illustrating portions of the rotatable jewelry cabinet which form no part of the claimed design.

1 Claim, 9 Drawing Sheets
